UNITED STATES PATENT OFFICE.

HUGO C. RASSMANN, OF BEAVER DAM, WISCONSIN, ASSIGNOR TO F. RASSMANN MANUFACTURING COMPANY, OF BEAVER DAM, WISCONSIN.

STALL CONSTRUCTION.

Application filed April 2, 1921. Serial No. 457,861.

To all whom it may concern:

Be it known that I, HUGO C. RASSMANN, a citizen of the United States, and a resident of Beaver Dam, in the county of Dodge 5 and State of Wisconsin, have invented certain new and useful Improvements in Stall Constructions; and I do hereby declare the following to be a full, clear, and exact description of the invention, such as will enable others skilled in the art to which it 10 appertains to make and use the same.

This invention relates to improvements in stall constructions and more particularly to stanchions and means for operating the 15 same,—one object being to provide simple and substantial means associated with a plurality of stanchions for easily and effectually opening or closing and locking all of the stanchions simultaneously or which may 20 be manipulated to open any one or more of a series of stanchions and leave the others closed and locked.

With this and other objects in view, the invention consists in certain novel features 25 of construction and combinations of parts as hereinafter set forth and pointed out in the claims.

In the accompanying drawings; Figure 1 is a plan view showing an embodiment of 30 my invention; Figure 2 is a side elevation of the same; Figures 3 and 4 are detail views and Figure 5 is a view showing a modification.

In the drawing, I have shown three stall 35 posts 1, 1, 1, representing two stalls 2, 2, and it will of course be understood that any desired number of stalls may be employed, and for each stall, a stanchion 3 is provided.

A horizontal bar 4 which may be said to 40 constitute the back-line of the stall structure, is rigidly secured to the upper ends of the several stall posts 1 by means of clamps 5,—one member of each of which is provided with a pair of arms 6, 6 which project laterally from respective sides of said 45 clamp member and each pair of arms 6, 6 constitute, in effect, a cross head rigid with the upper end of one of the stall posts. The arms forming said cross-heads are provided 50 at their free ends with suitable openings for the accommodation of bars 7, 8 which are movably supported by said arms or cross heads and disposed parallel with each other and with the central fixed bar 4 at respective 55 sides of and spaced from the latter.

Operating mechanism for the stanchions 3 is mounted on and associated with the stall superstructure and this mechanism includes a pair of brackets 9, 10, for each stanchion. The brackets 9, 10 of each pair 60 are provided at their ends with sleeves 11, 12 whereby they are movably mounted on the bars 7, 8. Each bracket 9 is made with a depending arm 13 terminating at its lower end in an elongated, horizontally disposed 65 flange or plate 14 having a plurality of holes 15 whereby one member of the stanchion may be adjustably connected therewith. The bracket 10 of each pair of brackets is also provided with a depending 70 arm 16 which terminates at its lower end in a horizontal flange 17, said flange having a plurality of holes 18 to permit a horizontal plate 19 to be adjustably secured to said flange. The plate 19 is disposed above the 75 horizontal plane of the flange 14 of the bracket arm 13 and its free edge is curved as at 20. The plate 19 is provided with a curved slot 21 which marks approximately 80 a semi-circle.

Each stanchion 3 comprises an approximately U-shaped frame or member 22 having horizontal arms 23, 24 at its upper and lower ends respectively, and a straight member 25 pivoted at its lower end to a sleeve 26 rigidly secured to the lower arm 24 of the U-shaped member 22 of the stanchion. The lower end of the stanchion may be loosely and adjustably connected by a chain 27 with a suitable anchor 28 at the bottom 90 of the stall.

The straight member 25 of the stanchion is provided with an upwardly and laterally projecting arm 29 having an opening 30 near its base through which the upper horizontal arm 23 of the stanchion member 22 passes freely. The free end portion of the arm 29 is vertically disposed and enters the curved slot 21 in the plate 19 carried by the bracket 10. The upper arm 23 of the stanchion member 22 has a collar 31 secured thereto and this collar is pivotally connected, through the medium of a headed pin 32 with the flange or plate 14 of the bracket 9 at any one of the holes 15 in said plate. In 105 this manner, the weight of the stanchion is sustained by the bracket 9.

It is evident that by providing for adjustable connection of the stanchion member 22 with the bracket 9 and adjustable 110

connection of the plate 19 with the bracket 10, the stanchion may be readily adjustable in the stall to accommodate cows of different sizes.

A link 33 is pivotally connected with each bracket 9 and a similar link 34 is pivotally connected with each bracket 10 and these links are adapted to be connected, respectively, with pins 35, 36 on the respective 10 slide bars 7 and 8, so that when said bars are moved,—one in one direction and the other in the opposite direction,—the brackets will be separated, one from the other and the stanchion connected therewith will be 15 opened. Should it be desired that one or more of the stanchions be not opened when the bars 7—8 are moved, the links 33—34 connected with the brackets 9—10 for such 20 stanchion or stanchions, will be disconnected from said bars 7 and 8 and connected with pins 37 on the central fixed bar 4, in which event the stanchion or stanchions will be locked in closed position.

For the purpose of moving the slide bars 25 7—8 in opposite directions respectively to open and close the stanchions, the devices now to be described may be employed: A hand lever 38 is pivotally supported between its ends on the stall post 1 at one end of the 30 series of stalls and one arm of this lever is connected by a rod or link 39 with one of the movable bars. In the drawing, I have shown a collar 40 on the bar 7 provided with a pin 41 to which one end of the rod or link is 35 pivotally connected. A cross bar 42 is pivotally attached centrally between its ends to the rigid central bar 4 and respective end portions of this cross bar are provided with elongated slots 43 to receive pins 44 on the 40 respective slide bars 7 and 8. It is apparent that when the lever 38 is depressed to impart longitudinal movement in one direction, the other slide bar 8 will, through the medium of the pivoted cross bar 42, be moved in the 45 opposite direction,—thus causing the brackets 9—10 connected with said bars 7—8 by the links 33, 34, to be separated and the stanchions opened.

Should any one of the stanchions be disposed in a position at or near right angles to the normal position shown in Figure 2, at the time that the mechanism is operated to open the stanchions, such stanchion will be pulled to its proper position before being 50 opened, by reason of the construction and arrangement of the connections between the members of the stanchion and the respective brackets as hereinbefore described and as shown in detail in Figures 3 and 4 of the 55 drawing,—said connections between the respective brackets 9 and 10 and the respective members of the stanchion being out of vertical alignment. Said connections are also 60 such as to afford ample freedom of motion 65 of the animal.

In the embodiment of my invention shown in Figure 5, two parallel bars 45—46 are provided for the accommodation of the brackets 47—48 by means of which the operation of the stanchion is effected. The parallel 70 bars 45—46 are supported by brackets 48 secured to the upper ends of stall posts 49—50,—the bar 45 being held stationary by said brackets and the bar 46 being movable longitudinally with relation thereto. The 75 bracket 47 with which the arm 29 at the upper end of the straight member 25 of the stanchion is connected, is securely clamped to the bar 45 and the bar 46 is movable with relation to this bracket. The bracket 48 with which the U-shaped member of the stanchion is connected is loosely mounted on the two bars 45, 46, and may be connected with one of said bars by means of a shiftable 80 pivoted link 51. An L-shaped hand lever 85 52 pivotally connected with the stall post 49 is connected by pivoted link 53 with the longitudinally movable or sliding bar 46.

A clamp 54 is secured to the sliding bar 46 and to this clamp the upper end of a 90 “sure-stop” bar 55 is pivotally connected, the lower portion of said bar 55 passing freely through a loop 56 clamped to the stall post 50.

It is apparent that when the parts are in 95 the positions shown in Figure 5, operation in one direction of the hand lever 52 will cause movement of the sliding bar 46 and of the bracket 48 and that when the latter is thus operated, the member 22 of the stanchion 100 will be moved relatively to the member 25 thereof and thus the stanchion will be opened. When the stanchion is thus opened, movement of the bar 46 will cause the “sure-stop” to close the opening between the stanchion and the other stall post, compelling 105 the animal to put her head in the stanchion.

Any one or more of the stanchions of a series may be locked in closed position by shifting one end of the link 51 from its 110 connection with the sliding bar 46 and connecting it at 57 with the fixed bar 45.

Various other changes might be made in the details of construction of my invention without departing from the spirit thereof or 115 limiting its scope, and hence I do not restrict myself to the precise details herein set forth.

Having fully described my invention, what I claim as new and desire to secure by Letters-Patent, is:—

1. The combination with a stall frame including a fixed top bar and a slidable top bar parallel therewith, and a stanchion comprising pivoted members, of brackets slidably engaged with the slidable bar and connected respectively with respective members of the stanchion, means for imparting endwise movement to the slidable bar, and a link pivoted at one end upon one of the brackets and engageable at its opposite end 125 130

with the slidable bar or with the fixed bar whereby the bracket may move with the slidable bar or permit the bar to slide through the bracket.

5. 2. The combination with a stall frame forming a plurality of stalls and including a fixed top bar and a slidable top bar parallel with the fixed bar, and a stanchion in each stall comprising pivoted members, of pairs of brackets slidably engaged with the slidable bar, the brackets of each pair being connected respectively with respective members of a stanchion, means for imparting endwise movement to the slidable bar, and

10 pairs of brackets slidably engaged with the slidable bar, the brackets of each pair being connected respectively with respective members of a stanchion, means for imparting endwise movement to the slidable bar, and links each pivoted at one end to a bracket and having its opposite end engageable with the slidable bar or with the fixed bar whereby the bracket may be caused to move with the bar or the bar may slide through the

20 bracket.

3. The combination with stall posts and a rigid bar connecting their upper end portions, and a stanchion between the stall posts and comprising pivoted members, of cross heads secured to said posts, longitudinally movable bars carried by said cross heads at respective sides of said fixed bar, a pair of brackets mounted on said movable bars and connected respectively with respective 25 members of the stanchion, a cross head pivoted between its ends to the central fixed bar and having movable connections with respective movable bars, a hand lever, means connecting said hand lever with one of the 30 movable bars, and means whereby the brackets may be connected either with the movable bars or with the fixed bar.

4. The combination with a stall frame, and a stanchion comprising pivoted mem-

bers, of brackets supported by said frame, a stanchion having one of its members pivotally connected with and supported by one of said brackets, a plate secured to the other bracket and having a segmental slot receiving a part on the other member of the stanchion, the pivotal connections between the respective stanchion members and the respective brackets being out of vertical alinement, and manually operable means for moving one of said brackets relatively to the other to open or close the stanchion.

5. The combination with a stall frame, and a stanchion comprising an approximately U-shaped member and a straight member pivoted thereto, said straight member having a hole through which the upper arm of the U-shaped member passes freely, and said straight member provided with an upwardly and inwardly projecting arm, of two slide brackets supported by the frame, manually operable means for moving said slide brackets simultaneously in reverse directions respectively, one of said slide brackets having a depending portion pivotally connected with the U-shaped member of the stanchion and supporting the weight of the latter, and the other slide bracket having a part loosely receiving the upper portion of the upwardly and inwardly projecting arm of the straight member of the stanchion.

In testimony whereof, I have signed this specification in the presence of two subscribing witnesses.

HUGO C. RASSMANN.
